UNITED STATES PATENT OFFICE.

EDWARD A. KOELLING, JR., OF ST. LOUIS, MISSOURI.

LOOSE-LEAF BINDER.

Application filed May 21, 1926. Serial No. 110,711.

This invention relates to loose leaf binders of the type in which parallel leaf-holding members such as bars are employed in conjunction with the means for adjusting the bars relatively to each other in order to vary the space between the same, together with means for holding the bars in their adjusted positions after the desired adjustment has been secured.

10 The primary object of the invention is to substantially improve and simplify the locking means that is carried by one of the bars for cooperation with the usual pins of the other bar in order that the bars may be 15 moved inwardly together but prevented from a reverse movement under tension of the means therebetween, means, of course, being provided whereby the bars may be moved in said reverse direction when desired 20 to remove or insert further sheets.

Other objects will become apparent as the nature of the invention is better understood by a consideration of the following specification in accompaniment with the drawing 25 forming a part of the application, and wherein:

Figure 1 is a side elevation of my improved binder.

Figure 2 is a top plan view thereof.

30 Figure 3 is a view partly in elevation and partly in section, for clearly disclosing the locking mechanism carried by one of the bar members for cooperation with the usual pins of the other bar member.

35 Figure 4 is a perspective of one of the pin-locking levers and a complementary block to which the same is pivotally secured.

40 My improved loose leaf binder consists of a pair of substantially parallel bars 5 and 6 of any desirable length, and preferably constructed of metal tubing, substantially rectangular in cross section.

The lower bar 6 is provided with the usual 45 vertically extending spaced posts 7-7 for extension through openings 8-8 in the top bar 5, to permit the bar 5 to be adjusted lengthwise of said posts and in this manner to accommodate any desired number of sheets which may be held clamped between 50 the bars 5 and 6.

The uppermost bar 5 carries a mechanism 55 for preventing the movement of this bar away from the lower bar 6, when sheets are clamped therebetween, as well as means for releasing said mechanism when it is de-

sired to accomplish such a movement of the bars with respect to each other, said mechanism being so constructed as to permit downward movement of the top bar 5 with respect to the lower bar 6 when such a movement is desired without the releasing of said mechanism.

60 The mechanism above mentioned consists in the provision of a pair of levers 9 and 10 that are pivotally secured as at 9' and 10' within the slots 11' of blocks 11-11 arranged within the uppermost bar 5 at the openings 8-8, said blocks being formed centrally with openings 11" that register with the openings in the upper bar as clearly 70 disclosed in Figure 3. The slots of the blocks communicate with the openings and each of the levers is formed at its inner end with a knife-edge nose 12 that will at all times project slightly into its respective 75 block opening 11" for biting engagement with the corresponding post 7 for preventing the upward movement of the top bar 5 upon the posts.

80 The tail portions of the levers 9 and 10 carry band springs 13-13, the free ends of which are slightly curved for engagement with the bottom wall of the tube 5 for normally so swinging the levers upon their pivots 9' and 10' as to maintain the knife-edge 85 noses of the levers within the openings 8-8 in the bar 5, for engagement with the posts 7-7, said springs obviously allowing the levers to be reversely swung upon their pivots in order that the bar 5 may be forcibly 90 moved downwardly at all time.

95 The upper and lower edges of the tail portions of the levers are inclined upwardly from their ends to allow the same to swing in reverse directions upon their pivots while the opposite edges of the nose portions are inclined, as shown, for the same purpose.

100 Slidably disposed within the upper bar member 5 between the levers 9 and 10 and in close contact with the under side of the top wall of said bar, is a longitudinally extending metallic strip 14 that is provided intermediate its end with a lug 15 that extends upwardly through a slot 16 in the top wall of said bar 5 and upon which is mounted an operating button 17 in order that said strip may be slid in opposite directions. The opposite ends of this strip 14 are provided with downwardly curved portions 18-18 that frictionally engage the upper edges of the 110

tail portions of said levers 9 and 10. The upper edge of the lever 10 is provided with an arcuate notch 19 in which the complementary curved end of the strip 14 is disposed, it being obvious that when the strip 14 is moved in a direction toward the left, thru the medium of the button 17, the curved ends of said strip will so engage the tail portions of the levers as to swing the same 10 downwardly upon their pivots in order to extend or move the knife-edge noses of the levers out of the openings 8—8 and consequently allow the upward movement of the bar 5 upon the posts 7—7. The levers will 15 be maintained in such a position thru the medium of the curved ends of the strips until said strip is forcibly moved in the opposite direction, at which time the springs 13—13 will forcibly swing the levers in a 20 reverse direction upon their pivots for again bringing the knife-edge noses of the levers into the openings 8—8, which is the locking position of the same.

The detailed features of construction and 25 operation of my invention will be understood by those skilled in the art and even though I have herein disclosed and described the most preferred embodiment of the invention with which I am at this time 30 cognizant, it is nevertheless to be understood that minor changes may be made

without departing from the spirit and scope of the appended claim.

Having thus described my invention, what I claim as new and desire to secure by Letters-Patent is:

In a file binder of the class described, a pair of parallel bar members, posts carried by one of said members for sliding engagement with openings in the other bar member, 40 pivoted levers mounted in said other bar member and having knife edges at their outer ends for projecting into the openings of said other bar member and for biting engagement with the posts, spring means 45 associated with the levers for normally holding them in biting engagement with the posts, a slideable bar mounted in said other bar member and having its opposite ends offset, said levers having inclined edges one 50 of which is provided with a notch, and the offset edges of the slide bar adapted to engage the inclined edges of the levers so that one offset end may rest in the notch, whereby 55 when the slideable bar is slid in one direction one offset end moves up the inclined edge of one lever and the other off-set end out of the notch of the other lever thereby swinging said levers to release them from biting engagement with the posts.

In testimony whereof I affix my signature.
EDWARD A. KOELLING, JR.
